UNITED STATES PATENT OFFICE.

DAVID ROSENTHAL, OF NEW YORK, N. Y.

DESIGN FOR A DOLL.

41,997.

Specification for Design. Patented Dec. 19, 1911.

Application filed February 7, 1911. Serial No. 607,204. Term of patent 3½ years.

To all whom it may concern:

Be it known that I, DAVID ROSENTHAL, a citizen of the United States, and a resident of the city of New York, borough of Manhattan, in the county and State of New York, have invented a new, original, and ornamental Design for a Doll, of which the following is a specification, reference being had to the accompanying drawing, forming a part thereof.

The figure is a front view of a girl doll, showing my improved design.

I claim:

The ornamental design for a doll as shown.

DAVID ROSENTHAL.

Witnesses:

GUSTAVE BAUER,
JOEL A. KRAUS.
